ATTORNEY

UNITED STATES PATENT OFFICE

WILLIAM LAUBER, OF MEADOWBROOK, PENNSYLVANIA

DESIGN FOR A STOCKING

Application filed February 5, 1929. Serial No. 29,947. Term of patent 14 years.

To all whom it may concern:

Be it known that I, WILLIAM LAUBER, a citizen of the United States, residing at Meadowbrook, in the county of Montgomery and State of Pennsylvania, have invented a new, original, and ornamental Design for a Stocking, of which the following is a specification, reference being had to the accompanying drawings, forming part thereof.

Figure 1 is a side view of a stocking showing my new design.

Figure 2 is a rear view thereof.

The design is illustrated in the drawings by dots which indicate holes in lacework formation in the stocking fabric.

The design is characterized by a plurality of triangles formed of lines of lace work enclosing a small central triangle formed of solid lacework, the triangles being spaced by intervening triangles formed of plain knit web, on each side of the vertical center line at the back of the stocking.

I claim:

The ornamental design for a stocking, as shown and described.

In testimony whereof I affix my signature hereto.

WILLIAM LAUBER.
